VACUUMIZING AND SEALING CONTAINER

Herbert A. Barnby, Toledo, Ohio, assignor to
Owens-Illinois Glass Company, a corporation
of Ohio

Application March 6, 1933, Serial No. 659,709

11 Claims. (Cl. 226—82)

My invention relates to a method and apparatus for vacuumizing and sealing bottles, jars or other containers within a vacuum chamber. It embodies certain modifications and improvements on the method and apparatus disclosed and claimed in my copending application Serial Number 613,892, filed May 27, 1932, on which Patent No. 1,967,346 was granted July 24, 1934. In said

10 patent I have shown a vacuum chamber in which are introduced the jars or other containers to be vacuumized, the caps for the containers being loosely placed in position on the containers. A sudden admission of atmospheric pressure within the vacuumized chamber serves to apply a sealing pressure to the caps. The amount of sealing pressure thus applied will evidently vary with the size of the mouth of the container. With wide mouth ware such as fruit jars and the like, the pressure may be ample to obtain an effective seal.

15

20 With narrow neck bottles, for example, the sealing pressure is evidently much less and may not be sufficient for effective and reliable operation.

An object of the present invention is to provide improved means by which the amount of pressure applied to the individual container caps is determined and controlled independently of the size of the caps or of the openings which are sealed. The invention further provides practical means for obtaining and applying to each individual 25 cap a greater sealing pressure than is obtainable by the application of the atmospheric air pressure directly to the caps. This increased sealing pressure permits effective and reliable sealing of narrow neck ware and also wide mouth ware 30 which does not have the exactness of finish required when the air pressure is applied directly to the caps.

More specifically, the present invention provides a baffle plate within the vacuum chamber 35 adapted to seat on the caps of jars or containers and serving as a pressure plate to receive atmospheric pressure and apply it to said caps when air is admitted to the chamber containing the vacuumized containers.

An object of the invention is to provide such a baffle plate so constructed that it will permit a substantially uniform distribution of the air pressure to the sealing caps therebeneath regardless of slight variations in the height of the containers.

A further object of the invention is to provide a novel and practical means for adjusting the clearance between the baffle plate and the surrounding walls of the chamber to thereby ad-

justably regulate the rate at which the atmospheric pressure applied to the upper surface of the plate is admitted to the body of the chamber beneath the plate, thereby adjustably regulating the amount of pressure applied to the sealing caps and the length of time the pressure is maintained.

Other objects of the invention will appear hereinafter.

In the accompanying drawings:

Figure 1 is a side elevation of an apparatus constructed in accordance with my invention. 10

Fig. 2 is a vertical section of such apparatus taken at the line II—II on Fig. 1.

Fig. 3 is a fragmentary perspective view showing one of the adjustable ends of the baffle plate. 15

Fig. 4 is a detail sectional elevation at the line IV—IV on Fig. 2.

Fig. 5 is a section at the line V—V on Fig. 4.

Fig. 6 is a side elevation showing part of the vacuum chamber and mechanism for operating 20 one of the doors.

Referring to the drawings, a vacuum chamber 10, the walls of which may be made of aluminum or other suitable material, is preferably 25 rectangular in form. The chamber is supported on a framework which includes angle bars or ribs 11 extending upward along the sides of the chamber, and cross pieces 12 extending across the top of the chamber and uniting the ribs 11. The ribs 11 and 12 may be cast integral with the 30 chamber walls for giving strength and rigidity to the structure. End gates or doors 13 close the ends of the vacuum chamber.

The doors are lifted and lowered for opening and closing the chamber by the following mechanism: Each door is carried on a pair of levers 14 and 15 on the front side of the chamber and a corresponding pair of levers on the opposite side of the chamber. The levers of each pair are substantially parallel when the door is in closed position. Each lever 14 is fulcrumed on a stud 16 formed in the side wall of the chamber, said lever including an arm 17 extending upward from the fulcrum. The arm 17 is connected through a link 18 to a counterbalancing coil spring 19, the latter being attached at its lower end to a screw bolt 20 anchored to a plate 21 at the bottom of the chamber. A nut 22 permits adjustment of the bolt for adjusting the tension of the spring. The lever 15 is pivoted at 23 to a stud on the chamber wall, and includes an arm 24 connected through a link 25 to a hand lever 26. The hand lever is fixed to a pivot shaft 27 mounted in brackets 28 at the upper corners of the vacuum chamber. Counterbalancing springs 19 are pref-

erably provided in connection with each of the levers 14 on both sides of the chamber.

The link and lever mechanisms are identical for the two doors, except that they are right and left handed. It will be evident that when the hand lever 26 is moved downward the two doors will be moved upward simultaneously to the broken line position as shown in Figure 1. The tension of the springs 19 may be adjusted to substantially counterbalance the weight of the doors, so that little effort is required in lifting or lowering the doors. The arrangement of the parts is such that the doors are substantially counterbalanced in all positions.

15 When the vacuum chamber is closed the air is exhausted therefrom by means of a vacuum pump (not shown) which withdraws the air from the chamber through an exhaust pipe 30 extending from the pump to the vacuum chamber and opening into said chamber through the upper wall thereof and preferably substantially at the center of said wall. A valve 31 in the vacuum line is operated by a hand wheel 32 and may be used as a throttle valve or for shutting off the pipe 30 from the vacuum chamber.

15 Jars or other containers 35 which may be filled with food products or other material which it is desired to vacuumize and seal within the container, are loaded on trays 36 before being introduced into the vacuum chamber. The trays are carried to and from the chamber on horizontal conveyors 37 extending from opposite ends of the chamber. As shown, a number of trays 36, each filled with jars 35, are placed one on top of another, all of the trays being then moved into the vacuum chamber. The receptacles 35 as herein shown are glass jars of usual construction provided with closures or caps 38. A sealing gasket is interposed between each container and its cap, the latter being placed loosely in position on the container before it is placed in the vacuum chamber. This permits vacuumizing of the container, followed by sealing of the cap thereon when air pressure is applied, as hereinafter set forth.

45 The baffle plate through which sealing pressure is applied to the vacuumized containers, and the mechanism for operating said plate, will now be described. This baffle or pressure plate 40 which may be made of flexible sheet metal is located in the upper part of the vacuum chamber and is approximately the length and width of the chamber. The plate may be made of sheet metal and is sufficiently thin, flexible and elastic to permit 50 it to accommodate itself to any slight variations in the top level of the closure caps on which it is seated during the sealing operation, as herein-after described. If desired, the baffle plate may be provided on its lower surface with a layer or covering of rubber, rubber composition or other suitable compressible, elastic material which will accommodate itself to any slight variations in the level of the closure caps and thus serve to equalize the distribution of pressure. This would permit the use of a more rigid baffle plate. The baffle plate 40, as shown, is formed with vertical depending flange portions 41 along its side margins. These flanges serve as guides for the plate and also give it sufficient stiffness and strength to permit it to be lifted and lowered without impairing its efficiency.

70 As shown in Fig. 2, only a slight clearance is provided between the side margins of the baffle plate and the opposite walls of the vacuum chamber, so that when air pressure is admitted above

75 the plate and causes it to apply a sealing pressure to the container caps 38, the passage of air downward to the space beneath the plate will be restricted and retarded to such extent that pressure of sufficient intensity and for a sufficient length of time to effect the desired sealing operation, will be maintained above the baffle plate.

The baffle plate 40 is automatically lifted when the doors 13 are lifted, and lowered when the doors are closed. For this purpose, operating 10 connections are provided between said plate and the door operating levers 14 as follows: Each of two vertical rods 43 (see Figs. 4 and 5) has a connection at its lower end with the baffle plate 40. This connection includes a disk 44 attached to 15 the lower end of the rod, said disk being anchored beneath a holding plate 45 attached to the upper face of the baffle plate by means of rivets 46 or other fastening devices. The opening in the plate 45 through which the rod 43 extends is large 20 enough to provide clearance on all sides of the rod and thus permit any lateral movement of the baffle plate which may be required to accommodate it to the surrounding walls of the vacuum chamber and to prevent binding of said plate. 25 The rod 43 extends upward through an opening in the top wall of the vacuum chamber and through a packing gland 47 by which air leakage is prevented. The upper end of each rod is attached to a cross bar 48. The rods may be screw threaded and provided with nuts 49 thereon above and below the cross bars to permit vertical adjustment of the baffle plate relative to the cross bars.

30 Vertical guide rods 50 are secured at their upper ends to the cross bars 48 and extend downward through bearing brackets 51 which may be attached to the angle bars 11. Links 52 are pivotally connected to the ends of the cross bars 48 and extend downward therefrom. The links are 35 provided with longitudinal slots 53 which engage pins 54 on the levers 14. This construction provides a lost motion connection between the levers 14 and the links, permitting the plate 40 to accommodate itself to the height of the containers 40 on which it rests. This connection is such that when the doors 13 are lifted by depressing the hand lever 26 the baffle plate 40 is permitted to remain seated on the containers until the doors in their upward movement reach an intermediate 45 position determined by the level of the baffle plate. The pins 54 which, during this movement, slide freely in the slots 53, are thus brought to the upper end of the slots so that during the final movement of the doors to their open position, 50 said links 52 are moved bodily upward, carrying with them the cross bars 48 and the baffle plate 40, the latter being thereby lifted away from the containers 35. In Fig. 6 the door 13 is shown in broken lines in the position at which, during its 55 upward movement, the lifting of the baffle plate is commenced.

In order to adjustably regulate the rate at which the atmospheric air is permitted to pass below the baffle plate during the sealing process, 60 the plate is provided with adjustable extensions, preferably at the ends of the plate. These include adjusting strips or plates 55 which may be coincident in length with the width of the baffle plate. These adjustment strips (see Fig. 3) lie 65 against either the upper or lower face of the plate 40 and are held in position by spring clamping strips 56 attached to the baffle plate. The strips 55 may be adjusted inward or outward to provide 70 any desired amount of clearance between the 75

plate and the end walls of the vacuum chamber, said strips being held in adjusted position by the yielding pressure of the clamps 56. A vacuum gauge 58 (Fig. 6) may be provided to indicate the 5 degree of vacuum within the vacuum chamber.

The operation may be summarized as follows: While the operating lever 26 is in its lowered position and the doors 13 lifted, the trays 36 with the containers 35 thereon are moved into the vacuum 10 chamber. The caps 38 are at this time seated loosely on the containers to permit the containers with their contents to be vacuumized. The lever 26 is now lifted, thereby lowering and closing the doors 13. During the lowering of the doors the 15 baffle plate 40 is also lowered so as to seat on the caps of the containers 35 in the uppermost tray. The valve 32 is open and the air is exhausted from the vacuum chamber through the exhaust pipe 30. This serves to exhaust the air from the 20 containers 35, the loose seating of the caps 38 permitting the escape of air from within the containers so that their contents are vacuumized to substantially the same degree as the vacuum chamber. When a sufficient degree of vacuum 25 has been drawn, atmospheric air is suddenly admitted to the pipe 30 by a quick opening of a valve 59 (Fig. 6). The air under atmospheric pressure passes through the pipe 30 and enters the vacuum chamber in the space above the baffle 30 plate 40. This air pressure on the upper face of the plate 40 is distributed and transmitted to the caps 38. The pressure is sufficient to hold the caps down in sealing engagement with the respective containers.

35 The air admitted above the plate 40 passes downward through the restricted space provided between the margins of the baffle plate and the adjoining walls of the vacuum chamber so that the pressure above and below said plate is quickly but not instantly equalized. The length of time the sealing pressure applied above the plate 40 remains effective can be adjusted and regulated by adjustment of the strips 55. The amount of pressure applied can be further regulated by 40 controlling the rate at which air is admitted through the pipe 30 to the pressure chamber. Owing to the flexibility of the plate 40, the sealing pressure is evenly distributed to the caps therebeneath even when there is a slight variation in 45 the top level of the caps, which frequently occurs in practice. This sealing pressure is transmitted through the containers in the uppermost tray and through said tray to the containers therebeneath. In this manner, all of the containers are sealed. 50 The trays may be provided with a facing of rubber or other compressible, elastic material, or may be made of sheet metal sufficiently thin and flexible to distribute the pressure in the same manner as above noted in connection with the pressure plate 55 40.

60 Modifications may be resorted to within the spirit and scope of my invention.

What I claim is:

1. The combination of a vacuum chamber, a 65 pressure plate within said chamber separating it into upper and lower compartments, said plate adapted to apply a sealing pressure to receptacles within the chamber beneath said plate, means for admitting air under pressure to the compartment above said plate and thereby causing the latter to apply a sealing pressure to said receptacles, said plate being sufficiently flexible to permit it to accommodate itself to inequalities in the height of the receptacles and thereby equalize the pressure transmitted to said receptacles, said plate

having its margins in close proximity to the walls of the vacuum chamber to provide a restricted passageway from the upper to the lower of said compartments by which air under pressure supplied to the upper compartment is gradually admitted to the lower compartment, and adjusting means for adjustably varying the restriction to the passage of air between said compartments. 5

2. The combination of a vacuum chamber, a pressure plate therein separating said chamber into 10 upper and lower compartments, means whereby said chamber is vacuumized, means for supplying air at atmospheric pressure to the upper compartment, said pressure plate being of such area relative to the horizontal area of the chamber as to provide a restricted passageway for the air from the upper to the lower compartment, and adjusting means to adjustably vary the restriction and thereby vary the rate at which the air passes from the 15 upper to the lower compartment 20

3. In a vacuumizing and sealing apparatus, the combination of a vacuum chamber substantially rectangular in horizontal cross section, a horizontally disposed baffle plate therein consisting of 25 flexible sheet material, said plate having vertically disposed marginal flange portions extending along the vertical side walls of the chamber and in close proximity thereto, said plate being approximately the length of the chamber, and means for adjustably varying the effective length of said plate. 30

4. In an apparatus for vacuumizing and sealing containers, the combination of a vacuum chamber substantially rectangular in horizontal cross section, a horizontally disposed sheet metal baffle plate within said chamber, said plate having approximately the horizontal dimensions of said chamber, the side margins of said plate extending vertically downward and reinforcing the plate, and an adjusting strip extending along one or both ends of said plate and adjustable lengthwise 40 of the plate for adjusting the effective length of the plate. 35

5. In a vacuumizing and sealing apparatus, the combination of a structure providing a vacuum chamber, a horizontally disposed baffle plate within 45 said chamber separating it into upper and lower compartments, a door for said chamber, an operating lever, connections between said lever and door for moving the latter to and from a closed position, and means by which said baffle plate is 50 lifted and lowered with the opening and closing movements of said door.

6. In a vacuumizing and sealing apparatus, the combination of a vacuum chamber, a horizontally disposed baffle plate therein, a door for said chamber, an operating lever, and operating connections 55 interconnecting the baffle plate, door, and lever, said lever being operable through said connections to open and close the door, and to lift the baffle plate to an inoperative position during the final 60 opening movement of the door.

7. In a vacuumizing and sealing apparatus, the combination of a vacuum chamber, a horizontally disposed baffle plate therein movable upward from an operative position in which it rests on containers within the chamber to be vacuumized, to an inoperative position in which it is spaced above the containers, a door for said chamber, a lever, and operating connections between said lever and the door and said plate for opening and closing 70 the door and for lifting said plate when the door is opened.

8. In a vacuumizing and sealing apparatus, the combination of a vacuum chamber, a horizontally disposed baffle plate therein movable upward from 75

an operative position in which it rests on containers within the chamber to be vacuumized, to an inoperative position in which it is spaced above the containers, a door for said chamber, operating mechanism for opening and closing said door, and means for lifting the baffle plate when the door is opened and lowering it when the door is closed, said means including a lost motion connection between the baffle plate and said operating mechanism by which the lifting and lowering of the baffle plate are effected during the final opening movement and initial closing movement of the door.

9. In a vacuumizing and sealing apparatus, the combination of a vacuum chamber, a horizontally disposed baffle plate within said chamber, supporting rods attached to said plate and extending upward through openings provided in the upper wall of said chamber, and means for lifting and lowering said rods and thereby lifting and lowering the baffle plate, said rods having a loose connection with said plate, permitting lateral movement of the plate relative to said rods.

10. In a vacuumizing and sealing apparatus, the combination of a vacuum chamber, a horizontally disposed baffle plate therein, vertical rods having a loose connection with said plate, permitting universal lateral adjustment of the plate rel-

ative to said rods, the latter extending upward from said plate through openings in the upper wall in the chamber, cross bars connected to the upper ends of said rods, vertical guide rods connected to said cross bars, guides for said rods mounted at the sides of said chamber, and means for lifting said cross bars and thereby lifting the baffle plate.

11. In a vacuumizing and sealing apparatus, the combination of a vacuum chamber, a horizontally disposed baffle plate therein, vertical rods having a loose connection with said plate, permitting universal lateral adjustment of the plate relative to said rods, the latter extending upward from said plate through openings in the upper wall in the chamber, cross bars connected to the upper ends of said rods, vertical guide rods connected to said cross bars, guides for said rods mounted at the sides of said chamber, doors forming the ends of said vacuum chamber, an operating lever, operating connections between the lever and the doors for opening and closing the latter, and means providing lost motion connections between said cross bars and said operating connections, whereby the baffle plate is lifted during the opening movements of the doors and lowered during the closing movements of the doors.

HERBERT A. BARNBY.
